UNITED STATES PATENT OFFICE

126,101

DESIGN FOR A STATUETTE

Wallace P. Vollmer, Wilton, Conn.

Application December 5, 1940, Serial No. 97,081

Term of patent 14 years

To all whom it may concern:

Be it known that I, Wallace P. Vollmer, citizen of the United States, residing at Wilton, in the county of Fairfield and State of Connecticut, have invented a new, original, and ornamental Design for a Statuette, of which the following is a specification, reference being had to the accompanying drawings, forming a part thereof, and in which:—

Fig. 2 is a side view thereof;

Fig. 3 is a top plan view thereof; and

Fig. 4 is a rear view thereof.

I claim:

The ornamental design for a statuette, as shown.

WALLACE P. VOLLMER.
